UNITED STATES PATENT OFFICE

LEONARD R. BENSON, OF WINDSOR, ONTARIO, CANADA.

BATH-BRUSH.

1,203,466.

Specification of Letters Patent. Patented Oct. 31, 1916.

Application filed February 29, 1916. Serial No. 81,233.

To all whom it may concern:

Be it known that I, LEONARD R. BENSON, a subject of the King of Great Britain, residing at Windsor, in the Province of Ontario and Dominion of Canada, have invented new and useful Improvements in Bath-Brushes, of which the following is a specification.

This invention relates to improvements in bath brushes and has particular application to a water driven revolving brush.

In carrying out the present invention, it is my purpose to provide a bath brush which may be connected to a bib or faucet and rotated by the water flowing through the faucet and through which the water may pass to facilitate cleansing of the body.

It is also my purpose to provide a device of the class described wherein the brush may be disconnected from the motor and a massage pad, sponge brush, or the like connected to the motor and utilized instead of the brush.

Another object of my invention is to provide a device of the type set forth which may be handled conveniently and easily and wherein the component parts will be so arranged and correlated as to reduce the possibility of derangement to a minimum.

With the above and other objects in view, the invention consists in the construction, combination and arrangement of parts hereinafter set forth in and falling within the scope of the claims.

In the accompanying drawings; Figure 1 is a view in side elevation of a device constructed in accordance with the present invention. Fig. 2 is a sectional view therethrough. Fig. 3 is a similar view taken at right angles to Fig. 2. Fig. 4 is a bottom plan view with the brush disconnected. Fig. 5 is a plan view of the brush.

Referring now to the drawings in detail, 1 designates a bell-shaped casing formed centrally with a pivot stud 2 projecting toward the open end of the casing. Formed integral with the casing 1, or otherwise connected thereto, is a hollow handle 3 opening into the casing 1 and rotatably mounted within the casing 1 upon the pivot stud 2 is a water wheel 4 of some suitable construction and of a shape corresponding to the shape of the casing. Secured to the end of the water wheel 4 adjacent to the open end 55 of the casing is a circular plate 5 formed with an annular flange 6 exteriorly screw-

threaded. The handle 3 is formed with an inlet nipple 7 adapted to be connected by means of a hose or the like, with a bib or faucet so that the water may pass through the handle 3 and discharge into the casing 1 against the blades of the water wheel to rotate the latter about the pivot stud 2. The outer side of the bell-shaped casing 1 at the open end thereof is preferably rabbed and secured within the rabbed portion is one end of a band 8 projecting beyond the open end of the casing and preferably formed of rubber or other pliable material and formed with openings 9.

10 designates a brush comprising a back 11, bristles 12 secured to one side of the back, and upwardly projecting lugs 13 secured to the opposite side of the back and spaced apart around the back in a circular 75 row and having the inner edges thereof screwthreaded to engage the flange 6 so that the brush may be attached to the water wheel.

Threaded through the casing 1 is a set 80 screw 14 adapted to engage the periphery of the circular plate 5 to hold the water wheel against movement when the brush is being attached thereto or disconnected therefrom.

In practice, the brush is connected to the water wheel and the nipple 7 connected to the bib or faucet by means of a hose or the like and the water passing through the hose and the handle impinges upon the blades of the water wheel 4 and so revolves the latter and the brush. The band 8 is placed in engagement with the body and upon pressure being applied through the medium of the handle to the casing the brush is brought into contact with the body. The back of the brush is preferably perforated as at 15 so that the exhaust water from the water wheel will pass through the brush and flow onto the body.

The back of the brush is preferably formed centrally with a pin 16 adapted to hold a cake of soap so that the water flowing from the water wheel through the brush may be soaped.

After the brush has been used it may be detached from the water wheel and a massage pad or sponge pad attached to the water wheel.

While I have herein shown and described the preferred form of my invention by way of illustration, I wish it to be understood

that I do not limit or confine myself to the precise details of construction herein described and delineated, as modification and variation may be made within the scope of the claims and without departing from the spirit of the invention.

I claim:

1. In a device of the class described, a casing, a hollow handle on said casing opening into the latter and having means thereon whereby the handle may be connected to a source of water supply, a water wheel rotatably mounted in said casing and adapted to be rotated by the water passing into the casing through said handle, a brush at the open end of said casing, a detachable connection between said brush and water wheel, and means for holding said water wheel stationary in the application of the brush thereto and the removal of the brush.
2. In a device of the class described, a

bell shaped casing, a hollow handle on said casing opening into the latter and having means thereon whereby the handle may be connected to a source of water supply, a water wheel rotatably mounted in said casing and adapted to be rotated by the water passing into the casing through said handle, a brush connected to said water wheel and arranged at the open end of said bell-shaped casing, the back of said brush being perforated whereby the exhaust water from the water wheel may pass through the brush, and means on the back of said brush adapted to hold a cake of soap.

In testimony whereof I affix my signature in presence of two witnesses.

LEONARD R. BENSON.
